[57] CLAIM

The ornamental design for a communications outlet
escutcheon for mounting on floor duct boxes, substantially
as shown and described.

DESCRIPTION

FIG. 1 is a perspective view of a communications outlet
escutcheon for mounting on floor duct boxes showing
my new design;

FIG. 2 is a front elevational view thereof;

FIG. 3 is a side elevational view taken from the right of
FIG. 2, the side opposite being a mirror image thereof;

FIG. 4 is a rear elevational view thereof;

FIG. 5 is a top plan view thereof;

FIG. 6 is a bottom plan view thereof;

FIG. 7 is a sectional view taken in the direction of the
arrows on line 7—7 of FIG. 2;FIG. 8 is a perspective view of a second embodiment of
the design of FIG. 1;

FIG. 9 is a front elevational view of FIG. 8;

FIG. 10 is a side elevational view taken from the right
of FIG. 9, the side opposite being a mirror image
thereof;

FIG. 11 is a rear elevational view of FIG. 8;

FIG. 12 is a top plan view of FIG. 8;

FIG. 13 is a bottom plan view of FIG. 8;

FIG. 14 is a sectional view taken in the direction of the
arrows on line 14—14 of FIG. 9.Fig. 1
